UNITED STATES PATENT OFFICE.

ERNEST M. ORLOW, OF WAUWATOSA, WISCONSIN, ASSIGNOR OF ONE-THIRD TO JOHN N. PETERSON, OF MILWAUKEE, WISCONSIN, AND ONE-THIRD TO ARTHUR J. SCHMITT, OF CHICAGO, ILLINOIS.

SEWING-MACHINE STAY-BUTTON LOCK.

Application filed December 23, 1922. Serial No. 608,659.

To all whom it may concern:

Be it known that I, ERNEST M. ORLOW, a citizen of the United States, and resident of Wauwatosa, in the county of Milwaukee and

5 State of Wisconsin, have invented certain new and useful Improvements in Sewing-Machine Stay-Button Locks; and I do hereby declare that the following is a full, clear, and exact description thereof.

10 Heretofore, in sewing on buttons on over-coats and similar objects by machine, a retainer has been employed for holding the large buttons in proper position and the stay button has been held immediately below the

15 large button. The parts which held the buttons are operatively connected with a sewing machine. In thus sewing on buttons difficulty has been experienced by reason of the fact that the stay button has been gripped 20 merely frictionally, so that there is nothing positively preventing rotation thereof. Thus the stay button is oftentimes moved into position where the holes therein are disaligned from the holes in the larger button,

25 with the result that the needle cannot be directed thru the openings in both buttons. This slows up the operation, breaks needles and has other disadvantages.

Applicant's device comprises means for 30 positively locking the stay button against rotation. The invention comprises diverse modifications, in all of which a positive grip is provided, adapted to effectually hold the button and retain it in proper position, the 35 operation of the grip being not a mere frictional engagement, but a positive button lock. The device is furthermore adapted to align the stay button and to retain it with the holes therein disposed immediately 40 below the holes in the larger button.

Applicant illustrates and describes diverse 45 modifications of his invention, but does not limit himself to details of construction or operating, and desires to embrace within the scope of the patented claim a substantial arrangement of equivalents.

Figure 1 is a plan of the invention, the large button being held over the novelly equipped parts and the foot plate.

50 Figure 2 is an elevation of the parts shown in Figure 1, the foot plate and parts thereon being shown in section.

Figure 3 is a plan of the foot plate and

novel lock mechanism with cover plate removed.

55 Figure 4 is a plan of a modified form of button.

Figure 5 is a section thru the button shown in Figure 4, showing the foot plate in section and the retaining jaws.

60 Figure 6 is a view similar to Figure 5, illustrating a modified form of button.

Figure 7 is a plan of a further modification of button and a further modification of lock.

65 Figure 8 is a plan of a still further modification of button and gripping jaws.

Pivoted to bar 10 at points 11-11' are a pair of arms 12-12', terminating in grips 13-13' between which the button 14 is positioned, the button lying over the bifurcations 15-15' of spring 16, secured at one end to bar 10. A stop 17 is downwardly directed between arms 12-12', being rigid with a slide 18.

70 It has been the practice heretofore to use these parts for holding button 14 in position, when it is being sewed to the article. Below bar 10 is a rod 19, to which a foot plate 20 is secured. On opposite sides of the upper face of the foot plate are spacers 21 which

75 are secured thereto, the spacers having openings 22-22' for the reception of screws 23, for securing cover plate 23' in position, the plate extending from one spacer to the other.

80 Pivoted at points 24-24' are a pair of jaws 25-25'. The jaw 25 has a finger 26 thereon and jaw 25, has a similar finger 26', the fingers being adapted to cooperate with a spring 27. The spring is arcuate in shape 85 and bent at its end to engage with the fingers. The tendency of the spring is to cause jaws 25-25' to approach. Between the jaws

90 an adjuster 28, is positioned, having a slot 29, therein, receiving a tongue 30, depending from cover plate 23'. Cover plate 23' is slotted to receive a screw 31, directed into an opening in the adjuster 28. The adjuster may be fixed in various positions in the slot.

95 The adjuster has inclined faces 33-33', adapted to contact with adjacent portions of the jaws 25-25', between which the stay button 34 is positioned. Obviously, the adjuster is operative to limit the movement of the jaws towards each other and to prevent

100 105 sidewise movement of the button, as side-

wise movement in one direction of each jaw is directly prevented. By moving the adjuster nearer the stay button 34, the jaws are caused to diverge from each other and separate a greater distance. The jaws 25—25' do not have a mere frictional grip on stay button 34. The stay button is provided with spaced notches 35, and jaw 25 is provided with a tooth 36, adapted to enter one of the notches 35. Jaw 25' is provided with a similar tooth 36' adapted to enter an opposite notch in the stay button. The spring 27 operates to retain the teeth effectually in the notches. The button and jaws cooperate 10 therefore to effectually prevent rotation of the button. As the jaws diverge from each other beyond the teeth 36—36' to the ends of the jaws, it is apparent that a button may readily be positioned between the jaws. If 15 desired, the button may be positioned by moving it downwardly from between the jaws or sliding it between the jaws on foot plate 20. In either case, the teeth and jaws cooperate with the button to so position it 20 that the holes 37 therein are in alignment with the holes 38 in button 14. The operation of the mechanism does not release the grip of the jaws as it does not merely frictionally retain the stay button, but effectually locks it in position, and apertures 37 cannot be disaligned from apertures 38. The rotary movement of the button is prevented by the teeth 36 which would have to be removed from notches 35 to permit the 35 position of the button to be changed. Bar 10 and rod 19 are operatively connected with sewing machine parts and are shifted thereby and operated in a manner well known in the art, so that after the thread has been directed thru openings in button 14 and stay button 34, the buttons may be shifted to direct the thread thru other openings in these buttons.

In Figures 4 and 5, a modified form of button 40 is shown, having a V shaped rib 41 thereon. Foot plate 42 is adapted to receive the rib, having a depression 43 therefor. Jaws 44—44' grip the sides of the button and prevent movement of the button 50 laterally. Rib 41 cooperates with the foot plate 42 to prevent rotation of the button and to lock it with its holes aligned with the holes in the upper button not shown.

In the modification shown in Figure 6, button 45 is provided with a groove receiv-

ing a rib 46 on foot plate 47, jaws 48—48' operating in the manner of jaws 44—44'.

In the modification shown in Figure 7, button 49 is provided with elongated holes 50, all substantially elliptical in shape. A pair of spaced fingers 51—51' project upwardly thru a pair of opposite holes, the fingers being received in the extreme ends of the holes, preventing lateral movement in any direction of the button. In this modification, the button is moved downwardly to position it over the fingers and the grooved surfaces of the fingers fit against the extreme limits of the holes. As in the other modification, the button rests upon foot plate 52.

In the modifications shown in Figure 8, the button 53 has rounded holes 54 therein. The button is substantially rectangular, but rounded at the corners. Between the rounded corners, the sides of the button are substantially straight. A pair of jaws 55—55' are provided for retaining the button, which may be slid in position between the ends 56—56'. Jaw 55 is provided with a pair of spaced teeth 57 and 58, each adapted to fit against the rounded corners of button 53. Jaw 55' is provided with teeth 57' and 58' adapted to contact with the other rounded corners of the button. Thus opposite sides of the button fit snugly in the recesses in each of the jaws, the recess being between the teeth.

In each of the modifications, the stay button may be readily positioned so as to dispose its holes in alignment with the holes of the larger button means being provided to effectually lock the stay button against rotation.

I claim:

A device of the class described, the combination of means for holding a stay button in position below a second button, with its holes aligned with the holes in said second button, and means for engaging said stay button, and means having interengaging means for locking said stay button against rotation, whereby thread may be directed thru aligned openings in said buttons for securing said buttons to an article.

In testimony that I claim the foregoing I have hereunto set my hand at Milwaukee, in the county of Milwaukee and State of Wisconsin.

ERNEST M. ORLOW.
